MOISTENING APPARATUS

Stephen Kokay, Chicago, Ill., assignor to Ditto,
Incorporated, Chicago, Ill., a corporation of
West Virginia

Application December 2, 1939, Serial No. 397,246

9 Claims. (Cl. 91—48)

This invention relates to moistening apparatus of a type adapted particularly for use in liquid process duplicating machines, in the operation of which copy sheets are fed into impression relationship with a master sheet, such copy sheets being first provided with a film of solvent by which the ink on the master sheet is softened sufficiently for insuring a limited transfer of such ink to the copy sheets. It is the object of this invention to provide an improved form and arrangement of parts for applying the solvent to the copy sheets.

The construction illustrated is more or less similar to that disclosed and claimed by my co-pending application, Serial No. 267,516, filed April 12, 1939, but it differs therefrom with respect to the means for applying the solvent upon the moistening roller by which the film of solvent is transferred to the several copy sheets in turn. In the arrangement as shown in the present application, the solvent is sprayed directly upon an auxiliary roller by which the solvent is transferred in the form of a thin film to the moistening roller, adjustable means being provided for controlling the pressure of the auxiliary roller on the moistening roller so as to control the thickness of the film of solvent applied and thus to control the amount of the ink transferred from the master sheet.

It is another object of the invention to provide an improved arrangement of parts in which the auxiliary roller is movable toward and from the moistening roller for controlling the pressure against the moistening roller, means being provided below the auxiliary roller for catching and carrying away any surplus solvent which may drip from the auxiliary roller. In the arrangement shown, the means for catching surplus solvent comprises a plate which serves also as guiding means for directing the copy sheets into the bite of the two rollers by which the copy sheets are forwarded.

It is another object of this invention to improve arrangements of this type in sundry details hereinafter pointed out. The preferred means by which the several objects have been attained are illustrated in the accompanying drawings, in which—

Fig. 1 is a longitudinal vertical section through a duplicating machine embodying my improvements;

Fig. 2 is a vertical cross sectional view taken substantially at the line 2—2 of Fig. 1;

Fig. 3 is a vertical sectional view taken substantially at the line 3—3 of Fig. 2;

Fig. 4 is a horizontal sectional view taken on an enlarged scale substantially at the line 4—4 of Fig. 3;

Fig. 5 is a vertical sectional view taken substantially at the line 5—5 of Fig. 4;

Fig. 6 is a view similar to a portion of Fig. 3 but showing a modified form of construction; and

Fig. 7 is a fragmentary enlarged sectional view illustrating in detail the construction of one of the rollers used.

Referring now to Figs. 1 to 5, in which corresponding parts are indicated by the same reference characters, 10 and 11 indicate frame members formed of sheet metal in the form of housings at opposite sides of the machine connected together at their lower ends by cross positioned frame parts 12. Each of the side frame members 10 and 11 is provided with a reinforcing plate 13 rigidly secured thereto. A drum 14 is rotatably mounted in position between the frame members 10 and 11 by means of a heavy shaft 15 which is provided with a gear 16 meshing with a pinion 17 rigidly mounted upon a shaft 18 which preferably is provided with a crank handle (not shown) for giving the drum 14 the desired rotary movement. As is usual in devices of this type, the drum 14 is provided with a series of grippers 19 mounted upon a shaft 20 and normally pressed by springs 21 into operative position for holding a master sheet 22 upon the face of the drum, as is clearly shown in Fig. 3.

Underneath the drum 14, a platen roller 23 is provided rotatably mounted between levers 24 by means of a heavy shaft 25, the levers 24 being pivotally mounted upon pins 26 carried by the framework of the machine. The lower ends of the levers 24 are provided with rods 27 rigidly mounted therein so as to bear at their forward ends against cams 28 rotatably mounted in position by means of a shaft 29. The arrangement is such that upon a rotation of the shaft 29 the levers 24 can be swung in clockwise direction in Fig. 1 for causing the impression roller 23 to press with the desired degree of pressure against the drum 14.

The means for forwarding copy sheets into the bite of the drum 14 and the platen roller 23 comprises two rollers 30 and 31 rotatably mounted in position between the frame members 10 and 11 by means of shafts 32 and 33 respectively, such rollers being mounted in cooperative relation to each other for moving copy sheets forwardly toward the right in Fig. 3 into the bite of the drum and the platen roller. In

the arrangement shown, the shaft 33 is supported by levers 34 at opposite sides of the machine pivotally mounted at intermediate points by means of machine screws 35, springs 36 being connected between the rear end portions of the levers and pins 37 carried by the frame members 13 for pressing the roller 31 forcibly against the roller 30.

For supporting a pile 38 of copy sheets in position to be fed one at a time to the forwarding rollers 30 and 31, I have provided a table 39 which at its forward edge extends into close proximity to the roller 31, as is best shown in Fig. 3. Adjustable side bars 40 of any suitable type are mounted upon the table 39 for holding the sheets 38 in superposed position with respect to each other.

The means for applying solvent upon the moistening roller 30 comprises an auxiliary roller 41 rotatably mounted between arms or levers 42 pivotally mounted by means of machine screws 43 secured by means of screw-threads in lugs 44 extending inwardly from the end frame members 19 and 11. At their upper ends, the levers 42 are provided with screw-threaded bolts 45 pivotally mounted thereon and extending rearwardly from the levers through lugs 46 carried by plates 47 rigidly mounted in position by means of the screws 35 and 43. Upon the rear ends of the bolts 45 in rear of the lugs 46, I have mounted coiled springs 48 which are pressed forwardly by thumb nuts 49 mounted by means of screw-threads on said bolts. The arrangement is such that the springs 48 serve to press the roller 41 forwardly toward the moistening roller 30 for controlling the pressure between said two rollers and causing the roller 41 to rotate in clockwise direction in Fig. 3 so as to carry its upper face portion toward the roller 30.

Means is provided for applying solvent upon the upper face of the roller 41, such means comprising a tube or pipe 50 provided with a series of perforations 51 in its lower face, such pipe being mounted in position for spraying solvent therefrom through the openings 51 upon the face of the roller 41. Solvent is supplied under pressure to the pipe 50 by means of a pump 52 of any suitable type arranged to take solvent from a receptacle 53 and deliver it through a pipe 54 connected with the pipe 50, as is best shown in Fig. 3. In the arrangement shown, a check valve 55 is provided in the pipe 54 for preventing return of the solvent through said pipe to the receptacle 53. The pump 52 is operated by means of a lever 56 pivotally mounted on the frame of the machine by means of a machine screw 57, the lever 56 being connected with the piston rod 58 of the pump, as is clearly shown in Fig. 1. A second lever 59 is pivotally mounted by means of the machine screw 57, with a lug 60 thereon engaging the bottom face of the lever 56 so that downward movement of the lever 59 causes upward movement of the lever 56. A roller 61 carried by the lever 59 is actuated by a cam 62 carried by the drum 14 so that the lever 59 is given a downward stroke upon each revolution of the drum, such stroke of the lever being effected against the action of a coiled spring 63 mounted between the lever 59 and a frame bar 64. The arrangement is such that upon each revolution of the drum the pump is given an operative stroke for delivering solvent from the receptacle upon the upper face of the roller 41 by which the solvent is carried immediately toward the roller 30 and deposited in the bight or trough between the rollers 30 and 41.

Underneath the roller 41, I have provided a shield 65 in the form of a cross plate carried by the vertically positioned frame plates 47, such cross plate being connected rigidly with end plates 66 so as to provide a shallow receptacle beneath the roller 41. At opposite ends, this shallow receptacle is connected with a drain pipe 67 which in turn is connected by a pipe 68 with the receptacle 53 for catching and returning to the receptacle any surplus solvent which may drip from the roller 41.

At opposite ends of the rollers 30 and 41, I have provided bearing blocks 69 carried by plates 70 secured at their upper ends upon the end plates 66 by means of rivets 71. As is best shown in Fig. 5, the bearing blocks 69 are slidably mounted upon pins 72 extending inwardly from the plates 70, such bearing blocks being pressed inwardly toward the rollers 41 and 30 by means of coiled springs 73 interposed between the blocks and the plates 70. The arrangement is such that the blocks 69 serve effectively as end seals for preventing the escape of solvent from the ends of the rollers 30 and 41, and particularly as a means to prevent solvent from passing around the roller ends and downwardly to the surface of the roller 30 below its engagement with the roller 41. The lower ends of the blocks extend down over the ends of the roller 41 to drain any solvent that is on the blocks away from the roller 30.

For protecting the master sheet 22 against possible splashing of solvent thereon, I have provided a shield 74 opposite the front face of the roller 30.

The means provided for rotating the moistening roller 30 comprises a large gear 75 constrained to rotate with the drum 14 and meshing with a pinion 76 rotatably mounted in position upon a stud 77 carried by the framework, such pinion 76 in turn meshing with a pinion 78 carried by the shaft 32 of said moistening roller 30. The arrangement is such that when the drum is driven in counterclockwise direction in Fig. 1, the roller 30 is driven also in counterclockwise direction at substantially the same surface speed so as to carry a copy sheet forwardly toward the right in Fig. 1 between the roller 30 and the cooperating roller 31. When a sheet is carried forward by the rollers 30 and 31, it is brought thereby into the bite of the drum 14 and the platen roller 23, the parts being driven in such timed relation as to cause the copy sheet to have the desired registration with the master sheet 22, as is well understood in devices of this type. From the drum 14 and the platen roller, the copy sheet passes forward into position in a tray 79. For effecting the desired registration of the copy sheet with the master sheet, the cam 62 is provided with a recess 80 at one point in its periphery adapted by engagement with the roller 61 to give the operator a signal, calling for the stoppage of the rotation of the drum for the insertion of a copy sheet into the bite of the forwarding rollers 30 and 31.

In operation, when the drum is stopped in the position as shown in Fig. 1, a copy sheet is fed from the pile 38 into the bite of the rollers 30 and 31, such sheet being directed into position by the forwardly extending portion of the table 39 and the shield plate 65. After a sheet is thus placed in operative position, the drum 14 is again rotated for carrying the copy sheet forward to the bite of the drum 14 and the platen roller 23 into registration with the master sheet 22 for the duplication of the master sheet subject matter

upon the top face of the copy sheet. The amount of ink transferred from the master sheet to the copy sheet depends both upon the amount of solvent carried by the moistening roller 30 and transferred to the copy sheet and the strength of pressure of the platen 23 against the drum. The thickness of the film of solvent upon the roller 30 is controlled largely by the pressure between the auxiliary roller 41 and the moistening roller 30, an increase in the pressure serving to cut down the thickness of the film of solvent applied upon the moistening roller 30.

I have found by the use of my invention that very satisfactory results have been attained, the film of solvent upon the moistening roller 30 being very even and very easily controlled so as to produce either light or heavy copies as desired and so as to conserve the master sheet to a high degree where heavy copies are not required.

In the arrangement as illustrated, the rollers 30 and 41 are of solid formation, being formed preferably of rubber or of composition resembling rubber, while the roller 31 is preferably formed of sponge rubber or the like. In the preferred form of construction, the faces of the rollers 30 and 31 are smooth and imperforate. The surface of the roller 41 is preferably covered with fine spaced longitudinally running grooves as shown at 41b in Fig. 7. These grooves are roughly about .002 inch to .003 inch in depth and width and are spaced apart about .005 inch. The roller 41 is preferably of a hard material such as a synthetic resin or casein plastic, metal, hard rubber or similar material that can be machined accurately and roughened uniformly. Also, this roller should be of substantial rigidity so as to avoid appreciably bending due to its pressure against the roller 30. In this combination the roller 30 is preferably somewhat softer and resilient so that a surface engagement (as contrasted to a line engagement) may be obtained between the rollers 41 and 30. With such a combination the amount of liquid passing between the rollers 41 and 30 may be correctly proportioned by the grooves 41b to apply the proper amount of moisture to a copy sheet.

For cutting down to a minimum the evaporation of solvent in the use of the machine, I have provided a cover plate 81 above the rollers 41 and 30 adapted normally to close the space between the plate 65 and the plate 74, such cover plate 81 being pivotally mounted upon rivets 82 so as to enable the plate readily to be swung upwardly and backwardly for access to the rollers when desired.

In the arrangement shown in Fig. 6, the construction is the same as that above described, except that an additional shield plate 83 is provided for preventing the solvent delivered by the pipe 59 from splashing upon the moistening roller 30 so as to insure more perfect control of the thickness of the film of solvent upon the moistening roller. In the arrangement shown, the shield plate 83 is supported by the pipe 59.

While I prefer to employ the construction and arrangement as shown, my invention is not to be limited to such construction and arrangement except so far as the claims may be so limited, it being understood that changes might well be made in the form and arrangement of parts without departing from my invention.

I claim:

1. A moistening apparatus comprising in combination two rollers rotatably mounted in position one above the other in cooperative relation

for moving a copy sheet forwardly between them, means for rotating said rollers in the direction for forwarding a copy sheet, a third roller rotatably mounted in engagement with the rear face of the upper one of said first-named two rollers, and means for applying a supply of solvent on said third roller at its upper face portion in position to be carried quickly to the downwardly moving face portion of said upper roller and spread thereon under pressure in the form of a thin film.

2. A moistening apparatus comprising in combination two rollers rotatably mounted in position one above the other in cooperative relation for moving a copy sheet forwardly between them, means for rotating said rollers in the direction for forwarding a copy sheet, a third roller rotatably mounted on an axis movable toward and from the upper one of said first-named two rollers so as to rotate in engagement with the rear face portion of said upper roller, means for applying a supply of liquid on said third roller so as to establish a pool of the liquid between said one roller and said third roller, yielding means for pressing said third roller toward said upper roller for causing said liquid to be spread in a thin film on said upper roller, and means for adjusting the effective strength of said yielding means for varying the thickness of the film of liquid applied to said upper roller.

3. A moistening apparatus comprising in combination two rollers rotatably mounted in position one above the other in cooperative relation for moving a copy sheet forwardly between them, means for rotating said rollers in the direction for forwarding a copy sheet, a third roller rotatably mounted in engagement with the upper one of said first-named two rollers, means for spraying a supply of liquid on said third roller so as to be spread under pressure in a thin film on said upper roller, and means for preventing the sprayed liquid from splashing onto said upper roller.

4. A moistening apparatus comprising in combination two rollers rotatably mounted in position one above the other in cooperative relation for moving a copy sheet forwardly between them, means for rotating said rollers in the direction for forwarding a copy sheet, a third roller rotatably mounted in engagement with the upper one of said first-named two rollers, means for spraying a supply of liquid on said third roller so as to be spread under pressure in a thin film on said upper roller, and a shield in the form of a plate depending from the spraying means serving to prevent the solvent from splashing directly onto said upper roller.

5. A moistening apparatus comprising in combination two rollers rotatably mounted in position one above the other in cooperative relation to each other for moving a copy sheet forwardly between them, means for rotating said rollers in the direction for forwarding a copy sheet, a third roller rotatably mounted in engagement with one of said two rollers, a plate extending toward said third roller in substantially radial position with respect thereto, and means for projecting a supply of liquid substantially along the face of said plate onto said third roller so as to be spread under pressure in a thin film on said one roller for application to a copy sheet forwarded in contact therewith.

6. A moistening apparatus comprising in combination two rollers rotatably mounted in posi-

tion one above the other in cooperative relation for moving a copy sheet forwardly between them, means for rotating said rollers in the direction for forwarding a copy sheet, a third roller rotatably mounted in engagement with one of said first-named two rollers, and means for applying a supply of solvent on said third roller at its upper face portion in position to be carried quickly to the downwardly moving face portion of said one roller and spread thereon under pressure in the form of a thin film.

7. A moistening apparatus comprising in combination two rollers rotatably mounted in position one above the other in cooperative relation for moving a copy sheet forwardly between them, means for rotating said rollers in the direction for forwarding a copy sheet, a third roller rotatably mounted in engagement with the upper one of said first-named two rollers, end seals bearing on the end faces of said third roller and the upper one of said first-named two rollers, said end seals having downwardly extending portions for directing any solvent thereon toward the third roller below its engagement with the upper roller.

8. A moistening apparatus comprising in combination two rollers rotatably mounted in position one above the other in cooperative relation for moving a copy sheet forwardly between them, means for rotating said rollers in the direction

10 for forwarding a copy sheet, a third roller rotatably mounted in engagement with the upper one of said first-named two rollers, end seals bearing on the end faces of said third roller and the upper one of said first-named two rollers, said end seals having downwardly extending portions for directing any solvent thereon toward the third roller below its engagement with the upper roller, said third roller having a hard surface uniformly finished with fine longitudinally running grooves.

9. A moistening apparatus comprising in combination two forwarding rollers rotatably mounted in position one above the other in cooperative relation for moving a copy sheet forwardly between them, means for rotating said rollers in the direction for forwarding a copy sheet, a third roller rotatably mounted in engagement with the upper forwarding roller, means for delivering a supply of liquid on said third roller above its line of contact with said upper forwarding roller for passage downwardly between the third roller and said upper forwarding roller so as to be spread in a thin film on the downwardly moving face portion of said upper forwarding roller, and means comprising a plate underneath said third roller serving to catch and carry away any surplus liquid dripping from said third roller and serving also as a guard for directing copy sheets thereunder to the bite of said forwarding rollers.

STEPHEN KOKAY.
